(57) **CLAIM**

We claim the ornamental design for a grill for a cooktop, as shown and described.

DESCRIPTION

FIG. 1 is a top, front, right perspective view including an environment of use of a first embodiment of a grill for a cooktop showing our new design;

FIG. 2 is a bottom, right perspective view of the grill of FIG. 1;

FIG. 3 is a top plan view of the grill of FIG. 1;

FIG. 4 is a bottom plan view of the grill of FIG. 1;

FIG. 5 is a left elevation view of the grill of FIG. 1;

FIG. 6 is a front elevation view of the grill of FIG. 1;

FIG. 7 is a top, front, right perspective view including an environment of use of a second embodiment of a grill for a cooktop showing our new design;

FIG. 8 is a bottom, right perspective view of the grill of FIG. 7;

FIG. 9 is a top plan view of the grill of FIG. 7;

FIG. 10 is a bottom plan view of the grill of FIG. 7;

FIG. 11 is a left elevation view of the grill of FIG. 7; and,

FIG. 12 is a front elevation view of the grill of FIG. 7.

The broken lines in FIGS. 1 and 7 are included for the purpose of illustrating portions of the environment in which the grill for a cooktop is used. The broken lines in FIGS. 1 and 7 form no part of the claimed design. The left and right elevation views of the first embodiment of the grill are identical. The left and right elevation views of the second embodiment of the grill are identical. The front and back elevation views of the first embodiment of the grill are identical. The front and back elevation views of the second embodiment of the grill are identical. Thus, only one view of the left and right elevation views and only one view front and back elevation views has been included.
